Mr.

UNITED STATES PATENT OFFICE.

HECTOR P. MAC LAGAN, OF CHICAGO, ILLINOIS, ASSIGNOR TO NATIONAL RHEOSTAT COMPANY, OF CHICAGO, ILLINOIS, A CORPORATION OF ARIZONA TERRITORY.

RESISTANCE-ADJUSTING DEVICE.

No. 870,042.

Specification of Letters Patent.

Patented Nov. 5, 1907.

Application filed October 11, 1905. Serial No. 282,282.

To all whom it may concern:

Be it known that I, HECTOR P. MAC LAGAN, a citizen of the United States, residing at Chicago, in the county of Cook and State of Illinois, have invented a certain 5 new and useful Improvement in Resistance-Adjusting Devices, of which the following is a full, clear, concise, and exact description, reference being had to the accompanying drawings, forming a part of this specification.

10 My invention relates to adjustable resistance devices and more particularly to such devices to be used for the regulation of smaller current flow, such as that flow through voltmeters, galvanometers, or other like delicate instruments, and the object of the invention 15 is to provide a device which is of very simple construction and therefore inexpensive, and which is more efficient and reliable than devices of a like character.

I am aware of prior devices for adjusting current flow such as devices in which carbon forms the resist- 20 ance medium. In these prior devices, however, the resistance conditions are not constant; that is, the coefficient of the resistance is not sufficiently small, con-sequently making such devices unreliable in the delicate class of work for which they are to be used. In 25 my invention, however, the material used is wire having a resistance coefficient which is practically zero and the resistance conditions for one position of the device will be practically constant.

The construction of my device will appear best by 30 reference to the accompanying drawing, in which

Figure 1 is a plan view, part of the cover thereof being removed, and Fig. 2 is a sectional view taken on line 2—2 of Fig. 1.

The resistance medium of the device is composed of 35 the wire 1 arranged to form the winding 2. This wire which is known on the market as I. A. I. A. wire, is of a certain composition which renders the coefficient thereof practically zero and which renders it very hard and tough. The winding is of cylindrical form as 40 shown, and the wire may be wound in any manner about the core 3. The winding is best arranged, how-ever, by having the core of some flexible material, such as paper, fiber, rubber or other flexible insulating material, which in its normal straight position is wound 45 with the wire and subsequently bent to assume the cylindrical shape as shown. To support the winding I provide a cylindrical core or block 4 also of insulating material, such as wood, and the winding core after the wires have been placed thereon is bent around the 50 cylindrical face 5 of the block to rest against the flange 6 and is then secured in place by being glued to the block, or, as shown, by means of screws or nails 7 driven through the core 3 into engagement with the block. The wire which is normally uninsulated is 55 wound around the core to leave insulating space be-

tween the coils, and after the winding is completed I apply insulating material between the coils, and I preferably use a solution of silicate of soda, this being easily applied with a brush and which eventually hardens to almost the consistency of glass and thus 60 also protects the windings against mechanical injury. The core 3 may also be covered with a coating of this material before the windings are applied. From the center of the block extends a pivot post 8 to which is pivoted the adjusting lever mechanism for engagement 65 with the resistance wire. The switch blade or contact lever 9 for this mechanism is of springy material and extends radially from the pivot post so that its end 10 may have pressing engagement along the upper edge 11 of the resistance winding, and as the switch lever 70 is rotated this end will travel successively over the ends of the various winding coils.

To actuate the switch blade I provide the actuating handle or lever 12 secured with the switch lever to the hub 13 to form a unitary structure which is held in 75 place on the pivot post by means of the pivot screw 14. The switch lever and actuating lever are spaced so that with the cover 15 in position the switch lever will be at the interior thereof and the actuating handle at the outside thereof. This cover when in position engages 80 about the outer edge of the flange 6 and may be secured thereto by nails or screws 16. To apply the cover the screw 14 is removed and the switch blade and the lever frame and the hub 13 can readily be slipped through the opening 17 through the cover, and 85 the screw being then again secured in position the de-vice is ready for operation and the parts thereof en-tirely inclosed and protected.

Suitable terminal posts may be provided for the terminals 18 and 19 of the winding, but I have shown the 90 terminal posts 20 and 21 extending through the mount-ing block to the base thereof and are provided with threaded openings 22 for receiving threaded terminal pins of leads. The pivot post for the actuating lever also extends through the mounting block and is also 95 provided with a threaded opening 23 for the reception of lead tips. One terminal of the circuit for which the resistance is to be adjusted connects with the switch blade pivot post, and the other limb of the circuit by connection to the terminals 20 and 21 serially includes 100 more or less of the resistance winding, depending upon the position of the switch blade with respect thereto. The insulating material, or sodium silicate in this case, is not applied to the edge 11 along which the end of the switch blade travels and thus good contact is as-sured.

A device of this kind constructed of the material and in the manner described and shown is very reliable and can be used for the most delicate work. The com-position of the wire used renders the resistance con- 110

stant and the resistance in circuit remains constant for one setting of the switch blade, irrespective of weather, temperature, or other conditions, which makes the device extremely useful and desirable when used in connection with such delicate instruments as voltmeters, galvanometers, or the like.

I do not wish to be limited, however, to the precise arrangement and treatment of the parts as shown and described, as changes may readily be made without departing from the spirit of the invention.

I claim as new, however, and desire to secure by Letters Patent:

1. In a device of the class described, the combination with a resistance winding formed of a wire wound transversely around a band across the edges thereof, of a contact lever adapted for engagement with the adjacent turns along one edge of the band.

2. In a device of the class described, the combination with a resistance winding formed of wire wound transversely around the wall of a cylindrical shell and across the edges thereof, of a rotatable contact lever pivoted at the center of said shell and having a contact for engagement with the ends of adjacent coils along an edge of said shell.

25 3. In a device of the class described, the combination with a cylindrical mounting block, of a resistance winding formed of wire wound transversely around the wall of a cylindrical shell across the edges thereof, said shell being mounted about the cylindrical face of the block, and a rotatable contact lever pivoted at the center of said block and having a contact for engaging the wire at the ends of adjacent coils along one edge of the shell.

4. In a device of the class described, the combination with a winding formed of wire wound around the wall of a cylindrical shell across the edges of the shell, of a contact lever pivoted at the center of said shell and adapted upon rotation to engage the wire at the end of the adjacent coils along one edge of the shell, an actuating lever for said contact lever, and a cover for said device disposed 40 between the actuating and the contact levers whereby said actuating lever will be at the outside of the cover and the contact lever at the inside of the cover.

5. In a device of the class described, the combination with a cylindrical mounting block, of a resistance coil in the form of a flexible sheet wound transversely with wire across the edges thereof and subsequently bent cylindrically to be secured about the cylindrical surface of the mounting block and engaging at its end with the end of adjacent coils along one edge of the sheet, the end of the 50 contact arm upon rotation of the arm passing along the edge of the sheet into successive engagement with the ends of adjacent coils.

6. In a device of the class described, the combination with a cylindrical mounting block, of a resistance coil thereon, said resistance coil being in the form of a continuous winding mounted on a flexible strip or ribbon subsequently bent into a cylindrical form to fit about the cylindrical edge of the mounting block, the upper edge of said coil extending a slight distance above the mounting 60 block, a lever pivoted at the center of the block, and a contact on said lever bearing against the upper edge of said winding, rotation of said lever causing said contact to be carried over the edge of the winding into successive engagement with the coils thereof.

65 7. In a device of the class described, the combination with a resistance winding wound with a non-insulated wire on a cylindrical shell, the coils of said winding being arranged longitudinally and adjacent to each other but separated slightly, insulating material applied to the winding to maintain insulation of the coils from each other, a contact lever at the center of said coil, and a contact at the end of said lever pressed by said lever into engagement with one edge of said cylindrically arranged winding, rotation of said lever causing said contact to be 70 carried successively into engagement with the coils on the winding.

8. In a device of the class described, the combination with a resistance coil composed of non-insulated wire wound transversely over a flexible strip or ribbon of insulating material, adjacent coils being slightly separated and the strip with the windings thereon being subsequently bent to form a cylindrical shell, insulating material in the form of sodium silicate applied between and on the winding to insulate the coils thereof and to protect them against mechanical injury, the top edge of the winding being left free from said insulating material, and a contact on said lever pressed thereby against the edge of the winding of the coil, rotation of the lever causing the contact to be carried about said edge into successive engagement with the coils of the winding.

9. In a device of the class described, the combination with a cylindrical mounting block having a horizontal flange at its lower end, of a resistance coil in the form of a continuous winding wound on a flexible strip or ribbon of insulating material subsequently bent in the form of a cylindrical shell and secured about the cylindrical edge of the mounting block to rest on said flange, the upper edge of said coil extending a distance above the mounting block, a pivot post at the center of said mounting block, a contact arm pivoted to said pivot post and engaging at its end on the upper edge of said winding, a separate actuating handle pivoted to said pivot post and secured to the contact lever, and an inclosing shell for the device adapted to be disposed between the actuating lever and the contact lever whereby the actuating lever only will be at the exterior of the cover, said cover being secured about the cylindrical edge of the flange.

10. An adjustable resistance device composed of a cylindrical mounting block of insulating material, a cylindrical shell secured about the mounting block, a resistance winding wound continuously about said shell to form transverse coils whose vertical edges are disposed to form a circular contact edge, an actuating arm pivoted at the center of the mounting block, and a contact on said arm held in spring engagement with said resistance edge, rotation of said arm causing said contact to be carried about said edge in successive engagement with the ends of the coils composing said edge.

11. An adjustable resistance device composed of a cylindrical mounting block of insulating material, a cylindrical shell secured about the mounting block, a resistance winding wound continuously about said shell to form transverse coils whose vertical edges are disposed to form a circular contact edge, an actuating arm pivoted at the center of the mounting block, and a contact on said arm held in spring engagement with said resistance edge, rotation of said arm causing said contact to be carried about said edge in successive engagement with the ends of the coils composing said edge, the wire forming the winding being normally uninsulated and wound to leave spaces between coils, said spaces being subsequently filled with insulating material adapted to harden to maintain electrical separation of the coils and to protect them against mechanical injury.

12. An adjustable resistance device composed of a cylindrical mounting block of insulating material, a cylindrical shell secured about the mounting block, a resistance winding wound continuously about said shell to form transverse coils whose vertical edges are disposed to form a circular contact edge, an actuating arm pivoted at the center of the mounting block, and a contact on said arm held in spring engagement with said resistance edge, rotation of said arm causing said contact to be carried about said edge in successive engagement with the ends of the coils composing said edge, the cylindrical shell being normally in the form of a band or ribbon by which the wire is wound and subsequently bent with the wire thereon into the cylindrical form.

In witness whereof, I hereunto subscribe my name this 9th day of October A. D., 1905.

HECTOR P. MAC LAGAN.
